DEVICE FOR RESTRICTING WARPING
OF DOORS

Harry A. Singer, Elwood, Ind.

Application April 23, 1946, Serial No. 664,403

2 Claims. (Cl. 20—38)

1

This invention relates to devices for restricting the warping of woodwork, such as panels, partitions, doors, and the like, and for straightening these members again when warped.

An object of the invention is to provide a device which can be used for straightening warped doors, and for maintaining them in straightened condition.

Another object of the invention is to provide a door-straightening device which is simple in construction, inexpensive to manufacture, and effective in operation.

A further object of the invention is to provide a door-straightening device which is adjustable and is thus capable of restoring a door which is quite badly warped.

Another object of the invention is to provide a door-straightening device which may be installed on any door without the need for special tools or skill, and without making any structural changes in the door itself.

Other and further objects and advantages of the invention will become apparent from the following description of a preferred embodiment thereof as illustrated in the accompanying drawings, and in which:

Figure 1 is a front elevation of a portion of a door with my improved door-straightener installed.

Figure 2 is a sectional view taken on line 2—2 of Figure 1.

Figure 3 is a sectional view taken on line 3—3 of Figure 1.

Figure 4 is an enlarged detail in fragment, of the right hand end of the torsion bar shown in Figure 1.

Figure 5 is an enlarged detail in fragment, of the left hand end of the torsion bar shown in Figure 1.

As illustrated, a door 2 set into and hinged to door frame 3 has vertical side members 4 and 6 connected by a horizontal member 8, wire mesh screen material 10 being set into and fastened in the openings 12 bounded by the side and horizontal members. Although a screen door is shown, it is to be understood that this is merely by way of illustration, and that my invention may be applied to doors and the like regardless of construction of the door, so long as a tendency to warp exists. When the door is constructed, the surfaces of the side and horizontal members on either face of the door all lie in the same plane. However, due to a variety of causes, chiefly the use of unseasoned or partly seasoned wood, the door may warp so that the

2

surfaces of the side and horizontal members on a given face of the door will not lie in the same plane. This condition can be corrected, and the door restored to plane condition by means of my invention which exerts twisting or torsional forces on the door for this purpose, thus bending it back into its original shape.

Employ a torsion bar or twisting rod 14, cylindrical in contour, although other shapes may be used, the rod 14 being almost as long as the door is wide. The rod 14 is preferably made of spring steel. One end 16 of the rod is flattened as best seen in Figure 5. The other end 18 of the rod 14 is bent at 20 at right angles to the body of the rod, as best seen in Figure 4, and is flattened at its tip 22. An aperture 24 is formed in the flattened tip 22 for the reception of a screw, as at 26, for holding the tip 22 securely against one of the side members of the door, such as a side member 6, into which the screw is driven.

A bracket 28 has two legs 30 and 32 with their ends 34 and 36 bent into parallelism and alignment as seen in Figure 3, the bracket being secured to vertical side member 4 by means of screws 38 extending through holes in leg ends 34 and 36 and into the side member 4. Spaced adjusting screws 40 and 42 are threaded into recesses 44 and 46 in leg 30, as shown in Figure 3, the shanks of the screws 40 and 42 extending through corresponding holes in clamping plate 48 which is thus pressed toward leg 30 as the adjusting screws are tightened. A transverse groove or channel 50 is formed in the outer surface of leg 30 intermediate the recesses 44 and 46.

The rod 14 is thus installed with one end 18 secured to the right vertical side member 6 and with its other end extending into the space 52 between the adjusting screws 40 and 42 and the leg 30 and clamping plate 48 and into the groove 50.

As seen in Figure 3, it will be noted that as the adjusting screws 40 and 42 are tightened, the clamping plate 48 exerts torsional force on the flattened end 16 of the rod 14 so as to tend to turn it clockwise, as observed in the view, toward parallelism with the plane of the clamping plate. The torsional force thus exerted is transmitted through the bar 14, pressing the portion 20 of the bar tightly against the right side member 6 of the door and drawing the end 22 and the upper portion of the side member 6 toward the observer, as seen in Figure 1, thus exerting a turning couple about location 18, and straightening the door. It is obvious that the position of the device including the bar 14 and the bracket 28

may be changed in its location and disposition on the door, to correct any type of warping, and that more than one bar and bracket may be used if desired. For an ordinary screen door, it has been found satisfactory to form the rod 14 of $\frac{1}{8}$ inch diameter spring steel, the bent end 18 being three inches long between points 20 and 22, and the width of flattened end 16 being one-half inch. The device is preferably applied to the inside of the door. When the door straightener is applied to a screen door it reinforces the door and also serves as a push bar for opening the door, thus protecting the screen.

Although I have described a preferred embodiment of my invention in specific terms, it is to be understood that various changes may be made in size, shape, material and arrangement without departing from the spirit and scope of the invention as claimed.

I claim:

1. A device for realigning two spaced portions and connected portions of a body warped with respect to each other, said device comprising a torsion bar extending across one side of said body between said portions, said bar having on one end a lateral arm of substantial length bearing along the surface of one of said portions, means fixing the outer end of said arm to said one portion and preventing said arm from pivoting away from said one portion in a direction corresponding to outward axial rotation of said bar, and means mounted on the remaining body portion and operatively engaging the end of said torsion bar opposite said lateral arm, said means being operable to axially rotate said torsion arm outwardly and hold said torsion arm tensioned with sufficient torsion to force and hold said portions into alignment with respect to each other, said means comprising a bracket fixed to said remaining body portion, a plate mounted on said bracket for movement toward and away from surface of said bracket, a transverse flat on the related end of said torsion bar positioned between said bracket and said plate, said flat being arranged at an angle to the surface of said bracket, with one edge engaged with said bracket surface to provide a fulcrum and with the opposite side edge engaged with said plate, said plate being movable toward said bracket in a

manner to tilt said flat toward said bracket surface and thereby axially torsion said torsion bar in an outward direction.

2. A device for realigning two spaced portions and connected portions of a body warped with respect to each other, said device comprising a torsion bar extending across one side of said body between said portions, said bar having on one end a lateral arm of substantial length bearing along the surface of one of said portions, means fixing the outer end of said arm to said one portion and preventing said arm from pivoting away from said one portion in a direction corresponding to outward axial rotation of said bar, and means mounted on the remaining body portion and operatively engaging the end of said torsion bar opposite said lateral arm, said means being operable to axially rotate said torsion arm outwardly and hold said torsion arm tensioned with sufficient torsion to force and hold said portions into alignment with respect to each other, said means comprising a bracket fixed to said remaining body portion, a plate mounted on said bracket for movement toward and away from surface of said bracket, a transverse flat on the related end of said torsion bar positioned between said bracket and said plate, said flat being arranged at an angle to the surface of said bracket, with one edge engaged with said bracket surface to provide a fulcrum and with the opposite side edge engaged with said plate, said plate being movable toward said bracket in a manner to tilt said flat toward said bracket surface and thereby axially torsion said torsion bar in an outward direction, and means for retaining said plate in position relative to said bracket to maintain said bar in torsioned condition.
